LEAF SPRING

Glenn F. Couch, Rochester, N. Y., assignor to
The Symington Company, New York, N. Y., a
corporation of Maryland

Application February 17, 1932, Serial No. 593,633

5 Claims. (Cl. 267—55)

This invention relates to leaf springs and, more particularly, to elliptic springs especially adapted for supporting a railway vehicle bolster from associated side frames.

5 The principal object of my invention, generally considered, is the provision of leaf or elliptic springs in which the effective span of the leaves is varied as the amplitude changes to avoid harmonic vibrations.

10 Another object of my invention is to provide a leaf or elliptic spring in which the ultimate capacity is gradually built up instead of being kept on a low plane, and then suddenly shot up to the ultimate capacity near the end of the compression.

15 A further object of my invention is the provision of a leaf or elliptic spring in which the effective span is decreased as the amplitude of compression or leaf deflection is increased, where-

20 by resonance is avoided.

A still further object of my invention is to provide a leaf or elliptic spring in which the period of vibration is varied or decreased as the amplitude is varied or increased, to thereby avoid

25 a cumulative increase in amplitude of vibration due to synchronous energizing forces.

Other objects and advantages of the invention relating to the particular arrangement and construction of the various parts will become apparent as the description proceeds.

Referring to the drawings illustrating my invention:

Figure 1 is a fragmentary elevational view of an elliptic spring embodying my invention, the spring bands and one end block being shown in section, and the leaves being shown in free position in full lines with the inner leaves shown in flexed position in dot-dash lines.

Figure 2 is an end elevation of the end block shown in Figure 1, on an enlarged scale.

Figure 3 is a sectional view of the end block on the line 3—3 of Fig. 2 looking in the direction of the arrows, illustrating the progressive movement of the line of contact between the upper engaging spring plate and the corresponding bearing surface on said block.

Figure 4 is a bottom plan of the block shown in Figures 2 and 3.

Figures 5, 6, 7 and 8 are views corresponding, respectively, to Figures 1 to 4, inclusive, but showing a modification.

Referring to the drawings in detail, like parts being designated by like reference characters, and first considering the embodiment of my invention illustrated in Figures 1 to 4, inclusive, an elliptic

spring 1 is fragmentarily shown, which spring may be utilized for the resilient support of any desired object, but is particularly adapted for the support of a railway vehicle bolster from an associated side frame. The spring 1 comprises a plurality of leaves or plates 2 of varying lengths providing the familiar stepped construction for each group or bank 3 of leaves. The center portions of said groups 3 are held together by bands 4, the outer portions 5, that is, the upper portion of the upper band and the lower portion of the lower band being preferably increased longitudinally of the leaves 2 to provide an enlarged supporting area 6, the full extent of which gradually comes into engagement with the outer surface 7 of the engaged plate 2, whereby the effective span of the spring leaves is gradually decreased as the spring is compressed.

This action is supplemented, in the present instance, by the novel form of the end blocks 8, only one of which is illustrated. Each end block comprises a pair of side portions 9 joined by an outer end web 10 and a body portion 11 preferably cored, as indicated at 12, to minimize weight. The end web 10 and the body portion 11 are desirably spaced, as shown most clearly in Figures 3 and 4, to receive the ends 13 of the innermost spring plates 14 which are curved toward one another to thereby interlock the end blocks in place. The end web 10 of the block 8 is desirably formed with an outer surface 15 sloping downwardly and outwardly to provide a badge plate area readily visible when the spring is used in a position below the normal eye level, as, for example, when it is used in a railway truck for supporting an associated bolster. The inner surface 16 is desirably sloped at its lower portion to correspond with the slope of the outer surface 15 and cut away intermediate its junctions with the sides 9 to avoid unnecessary weight, while still maintaining the requisite strength.

The body portion 11 of each end block 8 has upper and lower spring bearing surfaces 17 formed on such a curvature that the effective line of contact between the spring leaves 14 and said surfaces gradually moves inwardly as the elliptic spring is compressed or flexed, the construction desirably being such that the rate of inward movement approximates the rate of spring deflection, whereby the curve representing the spring stress, as compared with the amount of spring compression, gradually increases in steepness as the spring is compressed without any sharp increase near the point where the spring goes solid.

The body portion 11 of each end block 8 has upper and lower spring bearing surfaces 17 formed on such a curvature that the effective line of contact between the spring leaves 14 and said surfaces gradually moves inwardly as the elliptic spring is compressed or flexed, the construction desirably being such that the rate of inward movement approximates the rate of spring deflection, whereby the curve representing the spring stress, as compared with the amount of spring compression, gradually increases in steepness as the spring is compressed without any sharp increase near the point where the spring goes solid.

As an example of a preferred construction of the spring-engaging surfaces 17, it is pointed out that the surfaces in the present embodiment are curved about a relatively short radius 18 for the outer relatively short portion thereof and from the termination of said curved portions the bearing surface continues about a relatively long radius 19 for the balance of the supporting surface. In this way, it will be seen that the bearing surfaces are compoundly curved with the curvature sharper adjacent the outer end of the block than adjacent the inner end thereof.

The dot-dash lines radiating from the upper surface or bearing area 17 of the end block 8 represent successive positions of the lower spring plate 14 of the upper spring group, the circles 20, 21, 22, 23 and 24 indicating positions of tangency between the spring leaf 14 when in positions 25, 26, 27, 28 and 29, respectively. It will, therefore, be seen that as the spring leaf 14 and, of course, the other associated leaves deflect from the position 25 to the position 29, the span is progressively shortened the distance represented by the difference in positions between the places of tangency 20 and 24.

Although, in the present instance, the spring bands and end blocks are constructed so that they assist one another in providing increased stiffness for the spring as the spring is compressed, it will be understood that I may use my novel form of end block with conventional spring bands, or my spring bands with conventional end blocks, while still securing, in a measure, the desired result.

Referring now to the embodiment of my invention illustrated in Figures 5 to 8, inclusive, an elliptic spring 1^a is there shown which corresponds substantially with the spring 1 of the first embodiment, except that the spring bands 4^a are of conventional construction, such as may be used with the end blocks 8 of the first embodiment, and the end blocks 8^a have spring bearing surfaces 17^a curved differently from the surfaces 17, but so constructed that the desired result is attained as in the preceding embodiment.

In the present embodiment, the bearing surfaces 17^a on the spring blocks 8^a are curved about the relatively short radius 18^a at their outer portions and about the relatively long radius 19^a for the major portions of the area toward the inner sides thereof, thereby accomplishing a result similar to that accomplished by the end blocks of the first embodiment, except, of course, providing a force-absorption curve of somewhat different characteristics because of the difference in curvature of the bearing surfaces which thereby cause the position of tangency to travel across the bearing area in a slightly different manner. The end blocks 8^a may be constructed otherwise substantially as the end blocks 8 of the preceding embodiment, except that the inner surface 16^a is not shown inclined like the outer surface. It will be understood that, if desired, I may use bands for the spring of the present embodiment corresponding with the bands 4 of the preceding embodiment. Except as specifically described in connection with the present embodiment, the same may correspond with the preceding embodiment.

From the foregoing disclosure, it will be seen that I have devised a leaf spring which, in the embodiments disclosed, is generally designated as an elliptic spring, especially adapted for the support of a railway vehicle bolster. By constructing the bands and/or the end blocks so that the effective length of the spring varies, pref-

erably inversely with the amplitude of vibration or deflection, resonance or cumulative increase in amplitude of deflection from synchronism, or vibrating forces acting periodically in synchronism with the natural vibration period of the spring, is avoided. In other words, by providing that any change in amplitude immediately alters the span or free length of the spring, we have an automatically self-correcting device in that excessive amplitude alters the spring vibration period, so that what otherwise might be synchronous impulses do not act cumulatively to increase the amplitude of spring vibration.

Although I have disclosed certain preferred embodiments of my invention, it will be understood that modifications may be made within the spirit and scope of the appended claims.

I claim:

1. A leaf spring comprising a plurality of spaced end blocks and a spring leaf spanning the distance between them, each of said blocks having a curved bearing surface engaging said leaf, the curvature of each bearing surface being decreased as it approaches the other block.

2. An elliptic spring comprising a plurality of spaced end blocks and a set of spring leaves above and below said blocks and spanning the distance therebetween, each set comprising leaves of different lengths, the lengths of said leaves increasing to a maximum from the outer to the innermost leaves of said sets, each of said blocks having curved bearing surfaces engaging said innermost leaves, the ends of said innermost leaves only extending toward one another over the outer edges of said bearing surfaces, the curvature of said bearing surfaces being sharper adjacent the outer ends of the blocks than adjacent the inner ends thereof.

3. A leaf spring comprising a plurality of spaced end blocks, a set of spring leaves spanning the distance between said blocks, and a center band encircling said leaves, each of said blocks having a curved bearing surface engaging a leaf, the curvature of the bearing surface of each block being sharper adjacent the outer end of the block than adjacent the inner end thereof, that portion of said band engaging the outermost spring leaf being extended longitudinally of said leaf, beyond the normal contacting area therewith, so that upon flexing of the spring a greater than normal amount of supporting area is gradually presented to said leaf to thereby provide for a decrease in the effective span.

4. An end bearing block for leaf springs comprising side members joined by a body portion presenting curved bearing surfaces for engagement with leaf springs, the curvature of said bearing surfaces being sharper adjacent the outer end of said block than adjacent the inner end thereof.

5. A leaf spring comprising a pair of spaced end blocks, each of said blocks having curved upper and lower bearing surfaces, the radii of curvature of the surfaces of each block being relatively small at the outer ends away from the other block and increased toward the other block, and a pair of spring leaves spanning the distance between said blocks, one of said leaves engaging said upper surfaces and the other engaging said lower surfaces, so that as the spring is flexed the lines of engagement with the blocks travel from the portions of the bearing surfaces of relatively small radii to those of increased radii.
